ABSTRACT

There is disclosed a sequentially operative item-releasing display apparatus incorporating a coordinated series of moving elements which serve to effectively present a simulated path of movement for an item through the apparatus operating simultaneously with moving elements of an amusing nature and means producing an exciting sound, all for purposes of stimulating the imagination and amusing an individual, such as a child, viewing the device. Moreover, the device, at the end of its sequence of operation, releases a given item therefrom, thus creating the illusion that the item has followed the simulated path of movement through the device.

FIG. 8

SEQUENTIALLY OPERATIVE ITEM-RELEASING
DISPLAY APPARATUS

BACKGROUND OF THE INVENTION

This invention relates generally to display equipment, and is particularly concerned with the provision of a display apparatus incorporating a coordinated series of mechanical movements, light simulations, and sound effects that both attract and amuse an individual watching the device. Moreover, the invention is concerned with such a display unit which further serves to selectively dispense individual items therefrom at the termination of its coordinated sequentially operative program.

Various different types of display apparatus have previously been suggested. With each one, it has been generally recognized that the main purpose to be served thereby is the attraction of an individual's attention. Some forms of display devices are static in nature and attempt to attract the individual's attention by an imaginative and colorful presentation. Other forms of display equipment utilize sound for purposes of attracting the individual's attention, while still other forms of display devices utilize some type of dynamic light operation to attract the user's attention. Even further, mechanical movements of one sort or another are often incorporated in display equipment to achieve an attention attracting result. Commonly, a colorful static presentation is coupled with a particular mechanical movement in a given display presentation, and for many years, the attention attracting ability of a "blinking light" has been recognized. Notwithstanding the various different prior approaches which have been utilized, and/or suggested for utilization, in display equipment, there is a constant need, particularly in the domestic economy, for display devices that possess a unique attention attracting capacity, and one of the primary objects of the present invention is to satisfy this need. More particularly, a primary object hereof is to provide a unique display device which imaginatively integrates the effects of mechanical movement, dynamic lighting, and stimulating sound so as to create an amusing and enjoyable display machine.

Even further, an important and significant object of the present invention is to provide an apparatus conforming with the preceding objects and which is additionally so operative as to selectively and individually dispense a given item at the end of a programmed sequence of activities. In this regard, a somewhat more detailed, but still important, object of the present invention is to provide such a device wherein different portions of the dynamic lighting are sequentially activated for purposes of designating in the mind of the viewer an actual path of an item through the device, and wherein the item-releasing mechanism of the device is actuatable to release an item as if the same had traveled the path of movement designated by the dynamic lighting.

Again looking to the broader aspects of the invention, it should be noted that the invention contemplates taking full advantage of the attention attracting ability of complex mechanical movements without complicating the operating mechanism for the device itself. To this end, a further significant object of the present invention is to provide a display apparatus which utilizes rotary movement, reciprocating movement and serpentine movement in a simultaneous but coordinated pattern to achieve the given presentation. More specifically, a detailed object of the invention is to provide a display apparatus wherein certain moving components are rotated, wherein certain moving components are reciprocated, and wherein simultaneously simulated serpentine movement is achieved through the incorporation of sequentially operative lighting means. Moreover, this specific object of the invention further envisions the coordination with the movement of sound effects giving an overall visual and audio environment of a particularly exciting nature.

While the preceding discussion generally emphasizes some of the more basic aspects and objects of the instant invention, further specific objects hereof which should not be overlooked include the following:

- a. the provision of a display device or apparatus conforming with the preceding objects wherein at least one of the reciprocating movement mechanisms serves to move an attractive display element from a hidden to an exposed position and vice versa;
- b. to provide such a display device wherein at least one of the reciprocating movement mechanisms not only creates an attention getting movement, but additionally serves to integrate therewith the production of sound, as for example, through the movement of a "clapper" against a bell;
- c. to provide such a display device wherein reciprocating movement is easily achieved through the use of cams and cam followers and/or eccentric linkages;
- d. to provide such a display apparatus wherein a given sequentially operative presentation is initiated through use of a single switch;
- e. to provide such a display apparatus wherein a plurality of items to be dispensed can be stored therewithin but individually released therefrom at the end of a given sequential presentation;
- f. to provide such an apparatus wherein a substantial part of the audio presentation is reproduced through a speaker means operatively associated with a magnetic soundtrack and pickup head arrangement;
- g. to provide such a display device which can be continuously and efficiently operated and constructed from generally well known types of components and materials so as to be reproducible for widespread use.

30 The preferred embodiment of the invention incorporates a plurality of drive mechanisms for operating reciprocating and rotating elements, sequentially operative lighting means for designating a simulated path of movement of an object through the device, audio reproducing means for creating a 35 stimulating sound environment during the operation, item-releasing means, and control means for coordinating the driving mechanisms, lighting means, sound producing means and item-releasing means so that an effective presentation is made in sequential order ultimately resulting in the release of an individual item.

40 The invention will be better understood, and objects other than those set forth above will become apparent, when consideration is given to the following detailed description. Such description makes reference to the annexed drawings presenting a preferred and illustrative embodiment of the invention.

IN THE DRAWINGS

FIG. 1 is a front view of a display device constructed in accordance with the preferred embodiment of the invention;

50 FIG. 2 is a top view, partially in section, taken on the line 2-2 of FIG. 1;

55 FIG. 3 is a schematic side view of the reciprocating mechanisms preferably utilized in the device, FIG. 3 showing in some detail the operative nature of the arrangement shown in FIG. 2;

FIG. 4 is a detailed fragmental view of a storage chute and item-releasing mechanism incorporated in the apparatus of FIG. 1;

60 FIG. 5 is a fragmental detailed view of the item-releasing mechanism shown in FIG. 4;

FIG. 6 is a fragmental detailed view showing the disposition of lighting means incorporated in the apparatus of FIG. 1;

65 FIG. 7 is a detailed, partially schematic view, showing the preferred operative disposition of lighting means such as shown in FIG. 6, FIG. 7 designating the location of same as seen from the exterior of the apparatus; and

70 FIG. 8 is a schematic diagram showing an electrical system suitable for use in an apparatus constructed in accordance herewith.

If reference is now made to FIG. 1, it will be noted that the display device 2 shown therein includes a housing means 4 having a generally vertically disposed front face 6 and a generally horizontally disposed top face 8. As explained hereinafter, the display device 2 has located therein channel

means which open onto the front face 6 through an opening 10 in the lower portion thereof. Actuatable dispensing means, as also explained below, are utilized in the channel means for releasing individual objects therefrom so that the same pass through the opening 10 and into the release container or receptacle means 12. A plurality of wheel means, such as the simulated gears 14 and 16, are mounted for rotation adjacent and in front of the front face 6. A plurality of reciprocating means, such as the characters or decorative figures 18 and 20 and clapper 22 are mounted for reciprocation above the top face 8. Selectively operable means, including lighting means associated with the serpentine path 24 serve to indicate a path of movement of an object over the front face 6. Audio means, also discussed in more detail below, serve to produce an audible sound sequence, and control means are provided for rotating the wheel means, reciprocating the reciprocating means, powering the audio means, and operating the lighting means associated with the serpentine path, all over a determined period of time, and then actuating the means to release an object through the opening 10 in the front face 6.

Considering now the details of the rotating means and the reciprocating means, attention is directed to FIGS. 2 and 3. By reference to FIG. 2, it will be noted that the wheel means 14 is mounted on a shaft 30 journaled for rotation between the front face 6 of the housing means 2 and the rear face 6' thereof. The shaft 30 as shown in FIG. 3, further carries thereon a double ear cam 32. The cam 32 is located inside of but adjacent the front wall 6 of the housing, and the respectively oppositely disposed extending ears thereof cooperate with microswitch 34 (FIG. 3) mounted on and adjacent the top face 8 of the housing means 2. The microswitch 34, effects a stepping function particularly associated with the means for creating a simulated path of movement of an object through the device. This will become apparent, however, in relation to the description of FIG. 8.

Reverting again to FIGS. 2 and 3, it is to be noted that the shaft 30 further carries a sprocket 36 thereon about which is trained a chain 38. The chain 38 serves to drive the shaft 30 from a sprocket 40 mounted on a shaft 42. The shaft 42 is journaled between a pair of fixedly mounted bearing elements 44 and 46 and carries an additional sprocket 48 thereon about which is trained a chain 50 leading from a sprocket 52 carried on the outer end of the shaft 54 of a drive motor 56. Specifically, with operation of the motor 56, the shaft 54 is rotated to in turn rotate the sprocket 52. This drives the chain 50 which in turn drives the sprocket 48 and shaft 42. Shaft 42 thus rotates sprocket 40 driving chain 38 and chain 38 drives sprocket 36 so as to rotate shaft 30 thereby rotating the exposed wheel 14 and the internal double ear cam 32 to operate the microswitch 34. We thus have movement of one of the wheel means mentioned above and significantly, for purposes explained below, we have selective operation of the microswitch 34.

To obtain reciprocating movement of the character 18 shown in FIG. 1, the shaft 42 further has a cam element 58 eccentrically mounted thereon. This cam element is cooperatively associated with a cam follower 60 which, as shown in FIG. 3, is rotatably mounted at the lower end of a shaft 62. The shaft 62 extends vertically upward from the cam follower 60 and through a guide bearing 64 and an opening in the top face of the housing means 2 so as to support the character 18 above such top face. With rotation of the shaft 42, there is corresponding rotation of the cam element 58, and by virtue of the eccentric mount of such cam element, the cam follower 60, under the force of gravity, moves up and down, thereby imparting an up and down movement to the character 18. This up and down movement is illustratively designated by the respective solid line and dotted line positions of the character 18 in FIG. 1.

Further reciprocating movement is achieved with the character 20 from the same motor 56. To this end, it will be first noted from FIG. 3 that the upper face 8 of the housing means 2 includes a door 66 therein mounted for free pivotal

movement between the solid line and dotted line position there shown by means of a conventional high 68. Disposed immediately below the door 66 is the character 20 which preferably takes the form of an attractive puppet 70. This puppet 70 is mounted at the upper end of a shaft 72 mounted for reciprocating movement by a fixed bearing means 74. The lower end of the shaft 72 is pivotally coupled as at 76 to a further rod 78 that is eccentrically mounted by means of pivot 80 to a cam or crank element or wheel 82. The cam element or wheel 82 is mounted on a shaft 84 journaled in a pair of fixed support bearings 86 and 88. A sprocket 90 is fixed on the shaft 84 and has trained thereabout a chain 92 which leads to a drive sprocket 94 also carried on the shaft 54 of motor 56. Thus, as the motor 56 drives the shaft 54, the sprocket 94 serves to drive the chain 92 and in turn, the sprocket 90. The sprocket 90 drives the shaft 84 and in turn the cam wheel 82. Rotation of the cam wheel 82 imparts through the rod 78 a reciprocating motion to the shaft 72 and this in turn causes the puppet 70 to press upwardly through the door 66 to an exposed position. Continued rotation of the cam wheel results in the puppet moving back downwardly to its solid line position shown in FIG. 3, where it is hidden from view. In other words, the movement of the puppet is from a position hidden from view to an exposed position and then back.

It should be apparent that the rotating action of the wheel 14, the reciprocating action of the character 18 and the reciprocating action of the puppet 70 are all achieved through operation of the motor 56 and associated drive mechanisms which are essentially of the simple cam type.

Again referring to FIG. 1, it will be noted that an additional reciprocating means 22 and an additional wheel 16 are provided. This additional reciprocating means and additional wheel is driven by a second motor coordinated with that described above. More specifically, by referring to FIG. 3, it will be seen that projecting upwardly from the top face 8 of the housing means 2 and preferably rigidly secured thereto is a shaft or rod 96 which preferably carries a bell head 98 at the upper end thereof. The reciprocating means 22 includes a clapper head 100 carried on a shaft 102. The shaft 102 is pivotally secured as at 104 to a cam or crank wheel 106 mounted on a shaft 108. The shaft 108 is mounted between a pair of bearing brackets 110 and 112. Moreover, shaft 108 has a sprocket 109 thereon which has trained thereabout a chain 111 which leads from a drive sprocket 114 carried on the shaft 116 of a further motor 118. Accordingly, with operation of the motor 118, the shaft 116 is rotated thereby driving the sprocket 114 and in turn the chain 111 to drive the sprocket 109 which rotates the shaft 108 and in turn the cam wheel 106 to impart a reciprocating movement, in the lateral direction, to the shaft 102. This reciprocating lateral movement of the shaft 102 causes the clapper head 100 to selectively move into and out of engagement with the bell head 98 thereby causing a bell ringing operation.

The motor 118 further carries on the shaft 116 thereof a sprocket 120 which has trained thereabout a drive chain 122 leading to a drive sprocket 124 carried on a shaft 126. The shaft 126 is journaled for rotation in essentially the same manner as the shaft 30 so that the wheel 16 on the forward outer end thereof is disposed for rotation adjacent and in front of the front face 6 of the housing means 2.

The respective bearing brackets, guide bearings, and the like, are all mounted within the housing 2 by conventional means and accordingly further detailed discussion thereof appears unnecessary. It suffices to say that the mounting is such as to have the disposition of the respective elements in the operative associations shown in FIGS. 2 and 3 whereby two conventional motors such as the motors 56 and 118 can serve to drive in operating sequence the multiplicity of rotating and reciprocating elements yielding the ultimate imaginative and creative complex motion generally associated with the upper portion of the device as shown in FIG. 1. These mechanical movements and the cooperation of elements yielding such mechanical movements are of particular significance, but in

and of themselves do not create the overall unique presentation which can be accomplished in accordance with the preferred embodiment of the invention. To the contrary, the simulated path of movement as achieved by the lighting means, the environmental sound as created by the audio means, and the selective item release also contribute to the overall performance, and thus these other aspects will now be considered in detail.

The serpentine path 24 shown in FIG. 1 comprises part of a selectively operable means for indicating a path of movement of an object over the front face 6. The serpentine path 24 itself as explained in particular connection with FIGS. 6 and 7 actually designates the path behind which is disposed a plurality of lamp means spaced from each other within the housing. These lamp means 140 and 140', as shown in FIG. 6, each include a conventional small lamp 142 disposed in a conventional socket 144 having a pair of leads 146 and 148 leading therefrom. The respective leads 146 are preferably grounded as indicated, whereas the respective leads 148 are connected to an electrical system as described in particular relation to FIG. 8. It suffices to say for the present moment that there are a plurality of such light means mounted in spaced-apart relation relative to one another within the housing means 2 by any conventional technique. Disposed between the light means and the front face 6 or panel forming the front face 6 is a further panel 150 (FIG. 7) having a plurality of openings 152, 152a, etc., therein. These openings are preferably aligned with the respective lamp bulbs 142 so that the openings 152, 152a, etc., provide window means for each of the lamp means. Moreover, a sheet of translucent material such as the sheet 156 is preferably disposed between the panel forming the front face 6 and the panel 150 so that the lamp bulbs are normally hidden from view, but when illuminated, project their light through the aligned openings 152, 152a, etc., and in turn through the translucent sheet 156. Obviously, for this light to show to an individual viewing the device, the serpentine path 24 (FIG. 1) must either have openings itself therein or be a serpentine opening in the front face 6. Consistent with the preferred embodiment, the serpentine path 24 actually is defined by a cutout in the front face 6 which cutout has the translucent sheet 156 therebehind so as to close the front face and yet provide a means for the transmission of light through the serpentine path.

With the arrangement just described, a plurality of lamp means are disposed in spaced-apart relation within the housing means 2 and along a serpentine path. Window means associated therewith are provided by the panel 150 and translucent sheet 156 which overlies the panel 150 in relation to the lamp means, but which also underlies the panel forming the front face 6 so that the serpentine opening therein exposes the translucent sheet. The particular bracket or the like used for mounting each lamp means forms no part of the instant invention, and it suffices to understand that the lamp means are individually disposed in spaced relation to one another and along a predetermined path which, in this instance, is the serpentine path 24. With such an arrangement, if the lamp means disposed at the upper left of the serpentine path to the lamp means disposed at the base of the serpentine path near the outlet opening 10 (FIG. 1) of the device, then there will be a light spot type transmission through the translucent sheet 156 in stepped sequence, thus simulating the movement of an item through the apparatus over a predetermined path.

If attention is again directed to FIG. 3, it will be seen that there is shown in this figure a channel or chute means 180. This channel or chute means 180 has its upper end 182 so located that it can be reached through an opening of the device (not shown) either in the rear thereof or in the front thereof. Thus, particular items to be dispensed by the apparatus can be placed in the chute means 180.

The chute means 180 itself is probably best shown in FIG. 4. It includes an upper generally vertically disposed section 184 and a lower sloping but more horizontally disposed section

186. Items placed in the top opening 182 thus descend through the vertical section 184 of the chute means 180 to the downwardly sloping lower section 186 thereof. Operatively associated with the lower section 186 is an item dispensing mechanism 190. This item-dispensing mechanism 190 and the operation thereof can be better understood by reference to FIG. 5. Here, the lower downwardly sloping section 186 of the chute is shown as having an opening 188 in the top wall thereof. Mounted for pivotal movement in this opening is a U-shaped arm 190' movable between the solid line position there shown and the dotted line position there shown. In normal operation, a coil spring 192 with an extending finger 194 maintain the front depending arm 191 of the U-shaped release member 190' in a downward position. This results in having the opposed or rear depending arm 193 in the upper position. Therefore, an item to be dispensed such as the item 200 is free to move against the forward depending arm 191. However, only one item at a time will move within the limits defined by 20 the U-shaped release member 190' by virtue of the relative size of that member and the size of the items to be dispensed.

When it is desired to dispense an item, a solenoid 202 is activated, through the electrical leads 204 extending therefrom. This causes the plunger arm 206 of the solenoid to move upwardly, thereby lifting the forward end of the U-shaped release member 190' by virtue of the connection between the plunger arm 206 and the U-shaped member through a pivot bracket 208. Upward movement of the forward portion of the U-shaped member 190' results in downward movement of the rear portion or depending rear arm 193 thereof and this arm serves as a stop for the item which is immediately behind the item to be released. In other words, when the solenoid is operated, the rear arm 193 of the U-shaped release member 190' descends into blocking position within the chute portion 186, and simultaneously the forward stop arm 191 of the U-shaped release member 190' moves upwardly to thereby release the item previously disposed between the respective arms. The member so released then passes from the release member 190' downwardly in the chute portion 186 to and through the opening 10 (FIG. 1) in the front face 6 of the device and into the item-release container 12.

When the solenoid is no longer energized, the spring 192, acting through its projecting finger 194, serves to return the U-shaped release member 190' to its original position, thus permitting the next item to be released to pass under the rear depending arm 193 of the release member and into engagement with the front depending arm 191 thereof for a repeat of the operation just described. It should therefore be understood that the chute means 180 can be loaded with items to be dispensed and yet, these will be selectively released on an individual basis which, as explained more fully below, occurs at the end of a performance cycle of the display device.

Based on the preceding detailed description of the rotating means, the reciprocating means, the coordinated lamp and window means, and the item-dispensing means, the basic operating mechanisms of the present invention should be understandable to those of ordinary skill in the art. The only other environment producing operating device not yet described in detail is the audio reproducing means generally designated by the numeral 300 in FIGS. 2 and 3. This audio reproducing means can take any suitable form which will repeatedly reproduce an audio sequence in audible form in response to activation thereof and over a predetermined period of time. It has been found that a conventional arrangement having a magnetic tape wheel on which is recorded the sound sequence and a pickup head for reading the sound sequence, operates particularly well in the instant device when associated in conventional manner with a suitable transducer, such as a conventional speaker. The audio reproducing means thus appears to need little detail description except to understand that it is an integral part of the preferred embodiment constructed in accordance herewith and except to understand the manner in which it is sequentially operated.

With respect to sequential operation, particular attention is directed to the control means schematically shown by the electrical diagram of FIG. 8. This control means as shown in FIG. 8 is the specific control center to effect the preprogram sequence. In a broad sense consistent with the invention, the various drive mechanisms already described constitute in association with the electrical circuit to be described below, a control means for rotating the wheel means, reciprocating the reciprocating means, powering the audio means, and operating the selectively operable simulated path movement means for a predetermined period of time and then actuating the release means to dispense an object.

However, for purposes of understanding the operation of the invention, the arrangement of FIG. 8 is also referred to as a control means but significantly as the central control means rather than the overall control means.

The central control means generally designated by the numeral 400 in FIG. 8 incorporates a stepping switching means 402, a control circuit 404 and the microswitch 34 to which reference was previously made. Furthermore, it incorporates a pushbutton switch 406. The pushbutton switch is of conventional design as is the control circuit 404. When the pushbutton 406 is depressed, it serves to place the motors 56 and 118 and the audio reproducing means 300 in operative condition. To this end, it will be noted that the line 502 is connected by means of a line 504 with the audio reproducing means 300, the motor 118 and the motor 56. The other terminal of each of these devices is connected via line 506 to the control device 404. Upon depression of the pushbutton 406, the line 506 is connected with the other side of the input line, namely, the line designated 502. In essence, therefore, the audio reproducing means 300, motor 118, and motor 56, are energized. These continue to run or operate until the control circuit 404 shuts off the connection initially established by the pushbutton 406.

Leading to the control circuit 404 are lines 510 from the microswitch 34. As the microswitch is operated in the manner explained by the double ear cam 32, it effectively causes the control circuit 404 to step the stepping switch 402 one position. Thus, if the arm of the stepping switch (not shown) was originally in operative disposition for connection with the connection designated by point $x-n$, such stepping switch would move to position $x-1$. With the successive operation of the microswitch 34, such stepping switch would move to the position designated $x-2$. This movement of the stepping switch serves to establish a circuit to and through successive lamp means 140 so that the same are energized. During this entire time, the motors 56 and 118 remain in operation and the audio reproducing means 300 remains in operation. As the stepping switch energizes lamp after lamp after lamp, such stepping switch ultimately reaches its final step position, namely, $x-n$, and at this time a connection is established not only through the last lamp means in the sequence, if desired, but also through the solenoid 202 so as to raise the arm 206 thereof to position the release member 190 for release of an item. Accordingly, it will readily be understood that by means of a conventional stepping switch, only shown illustratively in FIG. 8, the lamps are sequentially operated in sequence ultimately resulting in operation of the item-release mechanism to dispense an item. When the stepping switch has reached the last position $x-n$, then the whole circuit is shut off. This means that the connection originally established by the circuit 404 across the line for the audio reproducing means 300 in the motors 56 and 118 is broken. Essentially, with conventional techniques, the pushbutton 406 serves to operate the control circuit 404 so as to step the stepping switch from a position $x-n$ to the first position in the sequence, namely, $x-1$. If the stepping switch includes a conventional continuous contact path, such as that designated by y , in addition to its selectively spaced connection terminals, $x-1$, $x-2$, etc., then the motors and audio reproducing means have their circuits established through the continuous conducting path y , whereas the lamp means referred to above have their circuits selectively

established through the respective contact points, and the release mechanism has its circuit established through the last of the contact points. The control circuit 404 is thus little more than a suitable relay to effect the wiring and suitable commutation means, both of any well-known type, which operate in the manner just described.

It should therefore be apparent that upon depressing the pushbutton 406 which is preferably mounted on the front face 6 of the device, as shown in FIG. 6, the respective motors 56 and 118 are set into operation for purposes of causing rotation of the wheel means 14 and 16, for purposes of causing reciprocation of the reciprocating elements 18, 20 and 22, for purposes of starting the audio sequence reproduced by the audio means 300, and for starting sequential illumination of the lamps 140, 140', etc., to designate a path of movement across the device. As the sequence continues, the systems remain in operation in the manner described until the central control system stepping switch reaches its last sequential position, whereupon the various electrically driven mechanisms are essentially shut off, with the solenoid 202 being activated at the last position to release a given item.

Having now described the invention in considerable detail, it is believed that those with basic mechanical knowledge, much less of ordinary skill in the art, will readily understand that the objects set forth at the outset of the present specification have been successfully achieved. Accordingly,

What is claimed is:

1. A display device comprising in combination:
  - a. housing means having a generally vertically disposed front face and a generally horizontally disposed top face;
  - b. channel means disposed within said housing means and opening on said front face thereof;
  - c. actuatable dispensing means in said channel means for releasing individual objects therefrom upon actuation thereof;
  - d. a plurality of wheel means mounted for rotation adjacent and in front of said front face;
  - e. a plurality of reciprocating means mounted for reciprocation above said top face;
  - f. selectively operable means for indicating a path of movement of an object over said front face;
  - g. audio means for producing an audible sound sequence; and
  - h. control means for rotating said wheel means, reciprocating said reciprocating means, powering said audio means, and operating said selectively operable means for a predetermined period of time and then actuating said actuatable means to release an object from said housing means.

2. A display device as defined in claim 1 further including means for starting said control means, and wherein said control means is operable upon starting for a single cycle of operation.

3. A display device as defined in claim 1 wherein said selectively operable means for indicating a path of movement of an object over said front face comprises window means extending along said path and a plurality of lamp means disposed in spaced relation to one another within said housing means and behind said window means.

4. A display device as defined in claim 1 wherein said rotating means comprise simulated gear means.

5. A display device as defined in claim 1 wherein said reciprocating means include decorative figures.

6. A display device as defined in claim 1 further including bell means mounted above said top face, and wherein said reciprocating means includes a reciprocating clapper disposed to cooperate with said bell means to effect ringing thereof.

7. A display device as defined in claim 1 wherein said path of movement has a serpentine configuration, wherein said selectively operable means for indicating a path of movement comprises sequentially operable spaced lamp means disposed within said housing along said path, and wherein said housing means includes window means along said path.

8. A display device as defined in claim 1 wherein said reciprocating means are operated by cam means.

9. A display device as defined in claim 1 wherein said control means comprises stepping relay switching means, wherein said selectively operable means for indicating movement comprises a plurality of lamps connected to said switching means for sequential operation thereby, and wherein said control

means further includes a switching device and cam means rotatable with one of said rotatable means, said cam means cooperating with said switching device to activate the same, said switching device being connected to said stepping relay switching means to cause the same to step and thereby operate said lamps.
